UNITED STATES PATENT OFFICE.

WILLIAM E. NICKERSON, OF CAMBRIDGE, MASSACHUSETTS.

ELECTRIC CONTROLLING MECHANISM FOR ELEVATORS.

SPECIFICATION forming part of Letters Patent No. 403,442, dated May 14, 1889.

Application filed March 9, 1889. Serial No. 302,709. (No model.)

To all whom it may concern:

Be it known that I, WILLIAM EMERY NICKERSON, of Cambridge, in the county of Middlesex and State of Massachusetts, have invented 5 certain new and useful Improvements in Electrical Controlling Mechanism for Elevators, of which the following, taken in connection with the accompanying drawings, is a specification.

My invention consists in placing upon the 10 walls of an elevator-well switch-plates in circuits and in connecting to the carriage an index-electrode to be operated by the attendant and to be so made and arranged that it can be set to cause a break in the circuit at any desired floor, so that the attendant can control 15 the motion of the carriage by simply turning the index-electrode.

My invention is shown in the accompanying drawings, in which—

20 Figure 1 is a view in vertical section showing the well-room of an elevator, the elevator-carriage, electric devices, and parts of the electric circuits and fixed circuit-breakers. Fig. 2 is a diagrammatical view showing the electric circuit and switch system. Fig. 3 is a vertical section showing a cam for contact-breaking and an index-electrode attached to it and also indexed contact-plates. In this figure the cam is represented as not being at any of the 25 fixed switch-plates. Fig. 4 is a view similar to Fig. 3, except that the cam for circuit-breaking is in an acting position and in contact with one of the push-plates F of a circuit-breaker. Fig. 5 shows a part of the elevator-well wall and a part of the carriage-wall and 30 one of the indexed contact-plates in horizontal section, also showing the contact-breaking cam and the index-electrode.

In Fig. 1, A represents the elevator-well 40 room, C the carriage, and C' the hoisting-rope.

U U' represent an electric device used for 45 controlling the mechanism that causes the carriage to ascend, and D D' the electric device used for controlling the mechanism that causes the carriage to descend.

E is a cable containing the wires for making 50 the various circuits between the electric devices, the switch-box E', and the circuit-breakers.

One set of circuit-breakers, $u^3 U^6 u^3 U^5 u^4 U^4 u^5 U^3$, is shown in Fig. 1. This set is used when the elevator-carriage is ascending. The

circuit-breaker $d^7 D^6$, Fig. 1, belongs to the set of circuit-breakers that is used when the carriage is coming down.

55

For convenience of reference I have shown two sets of circuit-breakers and the connection with the electric device and switch-box in a single diagram, Fig. 2.

The switch-box E' is shown enlarged in Figs. 60 3 and 4. This box contains the circuit-breaking cam T' and an index-electrode, T², for operating the cam T'. The cam T' rotates on a center, t, Figs. 1, 2, 3, and 4. Attached to the switch-box are contact-plates H and L. The 65 contact-plate H is used when the carriage is going up, and has numbers at each division or mark indicating the place to put the index-electrode T² for stopping at the desired floor. The contact-plate L is used for going down, 70 and is marked in the same manner as the plate H.

The arrangement of circuits is shown in Fig. 2. The up-going circuit consists of the wire U², leading from the electric device U U' 75 to the circuit-breaker plate U³; thence (supposing that all of the circuit-breakers are closed, as shown in the diagram) through the plate u^5 and its wire to the next breaker, U⁴ u⁴, and so on through all of this series of breakers to the wire U⁷, and through it to the contact-plate H; thence by the index-electrode T² (if it is in contact) to the wire T and back to the electric device U U'. The down-going circuit consists of the wire D², leading from the electric device D D' to the circuit-breaker D³, 85 thence through the plate d^4 and its wire to the circuit-breaker D⁴ d³, and so on through all of the circuit-breakers, through the wire D⁷ to the contact-plate L, and then through 90 the index-electrode T² (if it is in contact) to the wire T, and back to the electric device D D'.

It will be observed that the breakers each have a cam-shaped push-plate, F, and a push-pin, S, and that the projections of these push-plates vary—that is, the series for going up increases in projection from the second floor to the last, and vice versa, for the coming-down series.

The operation of the above-described device is as follows: If we suppose the carriage at the bottom and the index-electrode T² on insulation, as shown in Fig. 3, then there will

100

be no movement. To start the carriage the attendant turns the index-electrode T^2 onto the contact-plate H . This act will make a circuit through the wires U^7 T , &c., to the electric device U U' and start the carriage upward. The carriage will continue to ascend until the cam contact-breaker T' engages with one of the circuit-breakers—for instance, the one at the fourth floor, u^4 U^4 , Fig. 1—and by pressing back the push-plate F and pin S breaks the circuit and stops the carriage. The cam T' is so made that its projection from the carriage depends upon the angle at which the index-electrode T^2 stands, its greater projection being when the index-electrode stands horizontally, as shown in Fig. 3, and the projection is less and less as the index-electrode is turned in a direction either up or down from the horizontal, and as the push-plates F of the circuit-breakers stand at different degrees of projection from the walls of the well-room it is evident that if the cam T' is so turned as to project but little then it will not act on a push-plate F unless that plate projects to a comparatively greater distance from the walls of the well-room, so that the position of the index-electrode T^2 and the cam T' determines at which circuit-breaker the breaking of the circuit will take place, (and consequently at which floor.)

The numerals 2, 3, 4, and 5 on the contact-plate H indicate at what position the index-electrode T^2 is to be placed for stopping the carriage at any desired floor, (when going up,) and the numerals 4, 3, 2, and 1 on the contact-plate L indicate at what position the index-electrode T^2 is to be placed for stopping the carriage at any desired floor when going down. I have shown my invention in use when it is desirable to have two series of circuit-breakers, one to be used in ascending and one in descending, so arranged that the attendant can set the index-electrode for stopping at

any floor either in going up or down. A simpler device, or rather arrangement, can be made with but one set of circuit-breakers, in which case the attendant would be obliged to set the index-electrode just before he reaches the floor at which he desires to stop.

My invention is involved, primarily, in the single circuit-breaking device shown in Fig. 4, consisting in the circuit-breaking plates U^4 u^4 , a transmitting mechanism like S F , and the cam T' , in connection with electric circuits and electric devices.

I claim—

1. In an electrically-controlled elevator, the combination of a fixed automatically-operated circuit-breaker with an adjustable cam, an index-electrode, and connecting-circuits and electric devices, substantially as and for the purpose set forth.

2. In an electrically-controlled elevator, the combination of a series of fixed circuit-breakers in the well-room, one for each floor, with an elevator-carriage having an adjustable cam adapted to operate the circuit-breakers, an index-electrode, and connecting-circuits and electric devices, substantially as and for the purpose set forth.

3. In an electrically-controlled elevator, the combination of a series of circuit-breakers adapted for each floor by having different degrees of projections, as described, with an adjustable contact-breaker in the elevator-carriage operating in connection with circuits and electric devices, substantially as and for the purpose set forth.

In testimony whereof I have signed my name to this specification, in the presence of two subscribing witnesses, on this 8th day of March, A. D. 1889.

WILLIAM E. NICKERSON.
